UNITED STATES PATENT OFFICE.

CHARLES R. MAGUIRE, OF BALTIMORE, MARYLAND.

SPRING-BALANCE SCALE-PAN.

SPECIFICATION forming part of Letters Patent No. 351,274, dated October 19, 1886.

Application filed October 30, 1885. Serial No. 181,379. (No model.)

To all whom it may concern:

Be it known that I, CHARLES R. MAGUIRE, a citizen of the United States, residing at Baltimore, in the State of Maryland, have invented certain new and useful Improvements in Spring-Balance Scale-Pans, of which the following is a specification.

My invention relates to an improvement in scale-pans for spring-balances of that class which have dials, pointers, and hanging pans. The scale-pans of this description of scales are made of various materials, including wood, marble, and other material capable of absorbing grease, and from this cause it happens that a spring-balance which may have been accurately adjusted for the scale-pan when new will after the pan has become heavier by the absorption of grease (as they do when used by butchers and butter-dealers) show by the pointer to be out of adjustment.

The object of this invention, therefore, is to provide for the pans of this class of spring-balances a removable receptacle or pocket to contain lead, whereby upon changing the lead the balance may be regulated so as to show on the dial a proper position for the pointer without any change or removal of the pointer.

In the drawings hereto annexed, Figure 1 is a view of a scale-pan such as is employed with a spring-balance. Fig. 2 is a bottom view of the scale-pan, showing the detachable receptacle. Fig. 3 is a sectional perspective view of the scale-pan. Fig. 4 is a view, separately, of the receptacle or pocket ready for attachment to a scale-pan.

The particular scale-pan A and hanger B here shown are like that shown and described in Letters Patent of the United States, granted March 25, 1884, No. 295,785. It is needless, therefore, to fully describe these parts here.

It may be stated that my invention is applicable to any other of the well-known styles of scale-pan and hanger used with spring-balances.

In this instance let it be supposed that the scale-pan A is made of wood or marble, or other material that will absorb grease. To such a scale-pan I attach a receptacle or pocket, C, which may be made of metal either cast or

stamped into shape. The receptacle is open 50 on one side, d, and is provided with screw-holes e. Pieces of lead f are placed in the receptacle, and the open side of the latter is placed against the bottom surface of the scale-pan, and screws g are then passed from the 55 top side of the scale-pan through to and into the screw-holes e of the receptacle. By constructing the lead-receptacle in this manner—that is, having all its sides but one closed and providing it with screw-holes and placing the 60 one open side in contact with the scale-pan bottom and securing it thereto by screws—it may be readily attached to scale-pans already in use and as readily removed therefrom. It will thus be seen it is perfectly 65 adapted for the accomplishment of the object in view.

It has been stated the receptacle may be made of metal; but it also may be made of other material—such as wood and vulcanized 70 rubber—and the shape of it may vary from that shown in the drawings. It may also be attached by screws passed first through the holes of the receptacle and then into the bottom side of the scale-pan.

Scales or balances have heretofore had shot-receptacles attached to their pans for the purpose of putting the pan and scale in balance. I do not, therefore, claim such a device, broadly.

Having described my invention, I claim and desire to secure by Letters Patent of the United States—

The combination, with a spring-balance having a dial, pointer, and hanging scale-pan, A, 85 of a receptacle, C, closed on all sides but one, and having the one open side in contact with the scale-pan and secured thereto, substantially as described, whereby to permit of the ready attachment or removal of the receptacle, for 90 the purpose set forth.

In testimony whereof I affix my signature in presence of two witnesses.

CHARLES R. MAGUIRE.
